UNITED STATES PATENT OFFICE.

HERBERT W. CHENEY, OF MILWAUKEE, WISCONSIN, ASSIGNOR TO ALLIS-CHALMERS COMPANY, A CORPORATION OF NEW JERSEY.

MOTOR-OPERATED SWITCH.

1,028,993.

Specification of Letters Patent. Patented June 11, 1912.

Application filed April 3, 1909. Serial No. 437,729.

To all whom it may concern:

Be it known that I, HERBERT W. CHENEY, a citizen of the United States, residing at Milwaukee, in the county of Milwaukee and State of Wisconsin, have invented certain new and useful Improvements in Motor-Operated Switches, of which the following is a full, clear, and exact specification.

This invention relates to switches, and particularly to switches of the motor operated remote controlled type.

One of the objects of this invention is the provision of a switch of high capacity and having an operating mechanism which will open or close the switch in an effective manner and with absolute safety to the operator.

A further object is for the provision of controlling an operating means which will cause the switch to be opened and closed with exceedingly quick movements, and in a manner such that arcing is reduced to a minimum.

A still further object is the provision of motor operated remote controlled switch which is more simple in construction and more effective in operation than those which have been constructed heretofore.

In carrying out my invention, I employ a rotary switch, preferably of the double-break type, and having a shaft or drum which carries one or more movable switch members and which is designed to be shifted or rotated in the same direction for both the opening and closing movements. The switch operating mechanism includes an electric motor, preferably of the rotary type, which is connected to the shaft of the switch by means of a spring, such as a coil spring, in which energy is adapted to be stored by the motor so that the spring may, when intermittently released, cause the shaft or drum of the switch to be rotated step by step in the same direction to swing the movable contact member or members into and out of engagement with the stationary contacts or to close and open the switch. The movement of the shaft is preferably controlled by means of an electrically operated escapement which permits the shaft to be rotated by the tension of the spring, a sufficient distance to open or close the switch, and then after a certain angular movement of the shaft the escapement stops the latter. The spring is preferably wound by the motor

after each movement of the switch shaft so that the spring is maintained under nearly constant tension which is at all times sufficient to quickly turn the switch shaft when the movement is permitted by the escapement, the circuit of the motor being controlled by a pair of switches, one mounted on the switch board and the other having a drum on the switch shaft.

The invention may be briefly summarized as consisting in certain novel details of construction and combinations and arrangements of parts which will be described in the specification and set forth in the appended claims.

In the accompanying sheets of drawings, Figure 1 is a side elevation of a switch constructed in accordance with my invention, parts being broken away for the sake of clearness; Fig. 2 is a top plan view of the same, parts being broken away; Fig. 3 is a transverse section taken along the line 3—3 of Fig. 1 and showing the switch closed or the stationary and movable contact members in engagement; Fig. 4 is a top plan view of a portion of the operating mechanism of the switch, parts being broken away and showing particularly the relative positions of certain notches in the escapement disk when the switch is open. Fig. 5 is a partial transverse section taken through the structure of the switch proper, the switch being here shown open; and Fig. 6 is a diagrammatic view showing conventionally the switch and the different controlling and operating devices which are employed in connection therewith.

Referring now to the figures of the drawings, 10 represents the frame or casting including a lower horizontal portion 11 which supports the mechanism of the switch proper, and an upper terminal casing 12, which supports the major portion of the operating mechanism for the switch. This frame, which is rectangular in shape, is supported by a plurality of vertical columns 13, the frame having at the corners slotted or bifurcated portions which receive the columns and which are clamped between nuts 14 at the upper ends of the bolts.

Before taking up the switch controlling and operating mechanism, I shall first describe the preferred construction of the switch itself, which in this case is a rotary,

three pole, oil break switch. Extending downward through the horizontal portion 11 of the upper frame or casting are a number of vertical bolts 15, (in this case four in number,) and supported by these bolts are three slabs 16, 17, and 18 of insulating material, such as marble or slate, the different slabs being arranged in different horizontal planes, one vertically over the other and being supported and held suitable distances apart by means of nuts 18 on the bolts 15 and by spacing sleeves 19 surrounding the bolts. These slabs 16, 17, and 18 support part of the contact mechanism for the different poles of the switch and also divide the oil tank, to be referred to later, into compartments. The movable contact members of the switch are mounted upon a rotary vertical shaft, drum or spindle 20, which is preferably formed of insulating material such as wood, and which extends centrally through the casting and through the different insulating slabs. Passing vertically through the horizontal portion 11 of the casting, and extending different distances below the latter, are a number of pairs of contact rods, which carry the stationary contacts, these rods being arranged in a circle about the axis of the vertical switch shaft or drum 20 and being spaced angularly equal distances apart. Two of these rods, 21 and 22, located diametrically opposite each other, are secured in any suitable manner in a pair of insulating bushings 23 and 24, mounted in the upper insulating slab 16. These two rods have at their lower ends, which are located in the compartment or space between the slabs 16 and 17, a plurality of inwardly extending contact fingers 25 and 26, which constitute the stationary contacts for one pole of the switch and are adapted to be bridged by a movable bridging contact member 27 which is clamped to the shaft or drum 20 in a position such that the outer ends of this contact member 27 may be engaged by the free ends of the fingers. Another pair of diametrically opposite rods 28 and 29 are secured in insulating bushings 30 and 31, carried by the insulating slab 17, and have at their lower ends, which are located in the compartment between the slabs 17 and 18, spring contact fingers 30^a and 31^a shown in Figs. 1 and 3, and these fingers, which constitute the stationary contacts for the second pole of the switch, are adapted to be bridged by a movable bridging contact member 33 which is clamped to the shaft or drum 20 intermediate the slabs 17 and 18 in a manner such that it is displaced angularly 60° from the bridging contact member 27. The other two contact rods 34 and 35 are secured in a pair of bushings 36 and 37, which are carried by the lower slab 18, and the lower ends of these contact rods, which extend a short distance

below the slab 18, are provided respectively with spring contact fingers 38 and 39 which constitute the stationary contacts for the third pole and which are adapted to be bridged by a movable bridging contact member 40 which is secured to the lower end of the drum 20 in a position such that when the latter is rotated, the ends of the contact member 40 will be engaged by the free ends of the contact fingers. This bridging contact member 40 is spaced angularly 60° from each of the contact members 27 and 33. 70

The six contact rods all extend upward through the horizontal portion 11 of the casting into the terminal casing 12, and to 80 the upper ends of these contact rods are connected terminal rods 41 which extend outwardly beyond the terminal casing, and have connected to their free ends the main terminal conductors 42. Each contact rod and 85 each terminal rod is surrounded by a tube of insulation 41^a.

The contact mechanism of the switch is inclosed by an oil tank 130, the upper portion of which engages the lower side of the 90 horizontal portion 11 of the frame or casting, intermediate the bolts 13 and the bolts 15 which support the insulating slabs and contact mechanism.

Suitable mechanism is provided for supporting this tank and for raising and lowering the same so that the contacts can be inspected, and this mechanism is as follows: On opposite sides of the frame or casting are two vertical threaded shafts 43 and 44, 100 the upper ends of both of which are shown in Fig. 2 and a portion of the shaft 44 being shown also in Fig. 1. These two shafts are mounted for rotary movement and are engaged respectively by threaded lugs or 105 nuts 42^a which extend outwardly from the sides of the tank, so that the latter will be raised or lowered as the shafts 43 and 44 are rotated. Mounted in suitable bearings 45 on the side of the terminal casing 12 is a 110 horizontal shaft 46 which is provided at one end with a hand wheel 47 and at its opposite end with a bevel gear 48 which meshes with a bevel gear 49 at the upper end of the vertical shaft 44. The shaft 46 is also provided with a bevel gear 50 which engages a bevel gear 51 mounted upon a horizontal shaft 52 which extends through the terminal casing 12 to the opposite side thereof, and is provided at its opposite end with a bevel gear 53 which engages a bevel gear 54 secured to a shaft 55 mounted in bearings 56 on the side of the terminal casing and having at its end a bevel gear 57 which engages a bevel gear 58 on the upper end of vertical 115 shaft 43. Thus it will be seen that when the hand wheel 47 is turned in one direction or the other, the two shafts 43 and 44 will be rotated, causing the nuts 42^a to travel 120 downward or upward along the shafts and 125 130

causing the tank to be lowered or raised, depending upon the direction in which the hand wheel is turned.

The switch operating and controlling mechanism will now be explained. Upon the top of the terminal casing 12 is a frame 60 having an arm which extends inwardly toward the center of the switch and has a bearing 61 for a shaft 62 which is rigidly secured at its lower end to the upper end of the shaft or drum 20 of the switch, said shaft or drum 20 extending upwardly through the terminal casing 12, and having its upper end secured to the lower end of the shaft 62 by means of a mortise or tenon and slot connection and by transverse clamping bolts 63. Mounted upon the frame 60 is a small series rotary motor 64 having on the end of its shaft a pinion 65 which meshes with a gear 66 secured to a shaft 67 which is mounted in suitable bearings 68 carried by the frame 60. This shaft 67 is provided intermediate the bearings 68 with a thread constituting a worm and this worm engages a worm wheel 70 which surrounds but is loose upon the shaft 62. The shaft 62 is not driven directly by the motor but is driven by a coil spring 71 which is adapted to be wound or in which energy is stored by the motor, the spring having its inner end secured to the shaft 62 and its outer end secured to the worm wheel 70.

The spring 71, when wound up or when energy has been stored therein by the motor, tends to rotate the shaft or drum 20 continuously in one direction, and in order that the spring tension may be controlled so as to intermittently turn the drum 20 to open the switch and also to close the same, I have provided an electrically operated escapement of the following construction: Secured to the shaft 62 is an escapement disk 72, having four notches 73, 74, 75, and 76 which are arranged alternately on opposite sides of the disk and are adapted to be engaged by the jaws 77 and 78 of a pivoted escapement lever 79. These notches are not spaced 90° apart, but, as shown particularly in Figs. 1, 2, 4, and 6, the distance between the notches 75 and 76 and between the notches 73 and 74 is greater than the distances between the notches 74 and 75 and between the notches 73 and 76, although the notches 73 and 75 and the notches 74 and 76 are 180° apart. As will be apparent, the distance between, or the angular spacing of, these notches determines the extent of angular movement given to the switch drum when the latter is released by the escapement. It may be here stated that the notches are arranged as shown and described above in order that the movable contact members of the switch will be swung through arcs greater than half the angular distance between the corresponding stationary contacts of the

different poles, when the switch is opened, or in order that the movement of the switch drum and contacts will be greater when the switch is being opened than when it is being closed. The notches each have one side 70 which is at right angles to the surface of the disk or to the bottom of the notch, and another side which is inclined so that the jaws of the escapement lever will readily enter the notches as the disk is rotated. As 75 will be apparent, the two notches 73 and 75 are adapted to be engaged by the upper jaw 77 of the escapement lever 79 so as to stop the switch drum when the switch is closed, or when the bridging contacts are in engagement with the stationary contacts, and the notches 74 and 76 are adapted to be engaged by the lower jaw 78 of the escapement lever to stop the drum after the switch has been opened. 80

The escapement lever 79 is shifted by two solenoids or two solenoid coils 80 and 81 which have a single armature 82 adapted to be drawn upward by coil 80 or downward by coil 81, and which is pivotally connected 85 to the rear end of the escapement lever. Either coil 80 or coil 81 is adapted to have its circuit completed across the mains of the low voltage circuit, to be referred to presently, by means of a pair of switches 83 and 84, the former having a drum 85 which is secured to the worm wheel 70 and the latter being mounted upon a switch-board at some distance from the oil switch or main switch. By referring to Figs. 1 and 6, it is seen that 90 the switch drum 85 of the switch 83 has two contact surfaces 86 and 87 which are adapted to be engaged by two sets or pairs of contact fingers 88 and 89, the fingers of each pair being insulated from each other. 95

Reference will now be had to the diagrammatical view of Fig. 6. In this figure the conductors of the main circuit or of the high voltage circuit which in this case is a three phase circuit are designated respectively 100 90, 91, and 92, and in this circuit is a three pole switch, the construction of which has been described and which in its entirety will be designated A. The conductors of the low voltage operating circuit are shown at 93 and 94 respectively. At 95 is shown an overload relay comprising a pair of contacts 96 and 97 adapted to be bridged by a contact member 98 carried by the core 99 of a solenoid having a coil 100 located in the secondary circuit of the small series transformer 101, the primary coil of which is located in the conductor 90 of the main high-voltage circuit. The contact 97 of the overload relay is connected by conductor 102 to 105 an overload solenoid coil 103 and thence to conductor 94 of the operating circuit, and contact 96 of the overload relay is connected by conductor 104 to conductor 93 of the operating circuit. The solenoid coil 103 co- 110

115

120

125

130

operates with a core 105 which is connected to the blade of a double-throw switch 84, which was referred to previously, and which is mounted on the switch board. One of the stationary contacts 106 of the switch 84 is connected by conductor 107 to one of the contacts of the set or pair 89 of the switch 83 and the other contact 89 of the same pair is connected to one end of coil 80 of the controlling solenoid of the escapement. Another stationary contact 109 of the switch 84 is connected by a conductor 110 to one of the contacts of the pair 88 of the switch 83, and the other contact of this pair of contacts is connected by conductor 111 to one end of coil 81 of the escapement controlling solenoid. The opposite ends of these two solenoid coils 80 and 81 are connected to the motor 64 by conductor 112 and this motor is connected by conductor 113 to conductor 104 which, as stated before, is connected to conductor 93 of the operating circuit. As shown clearly in Fig. 6, the conductor 102, which is connected to conductor 94 of the operating circuit and to contact 97 of the overload relay, is connected by conductor 114 to the middle contact or conducting member to which the blade of the switch 84 is pivoted. In Fig. 6 the main switch A is shown in its closed position and is retained in this position by the upper jaw 77 of the escapement lever 79, which engages the notch 75 in the upper face of the escapement disk 72. When the main switch is in this position the switch 84 on the switch-board will be in one of its extreme positions with the blade in engagement with the stationary contact 106. Also the switch 83, which has its drum 85 secured to the worm wheel, will be in position such that a contact strip of the drum will bridge the two contact fingers 88, while the two contact fingers 89 will be on one of the non-conducting portions of the drum so that when the switch A is closed and the series motor and other parts are stationary, the circuit through the series motor and coil 80 and escapement controlling solenoid is interrupted or broken by the non-conducting portion of the drum 85 of the switch 83, and the circuit through the motor and coil 81 of the escapement controlling solenoid is broken at the contact 109 of switch 84. If, however, the switch 84 is thrown by hand so that the switch blade will engage stationary contact 109, or in case the current in main conductor 90 rises to a predetermined amount and the bridging contact 98 of the overload relay is brought into engagement with the contacts 96 and 97 of the relay to complete the circuit through the solenoid coil 103 of switch 84 and shift the solenoid core 105 to bring the blade of switch 84 into engagement with the stationary contact 109, the circuit is immediately completed across the conductors of the operat-

ing circuit 93—94 through coil 81 of the escapement controlling solenoid and the series motor 64. The escapement lever 79 will therefore be at once shifted so that jaw 77 will be drawn out of the notch 75 and the jaw 78 will be brought against the lower surface of the disk, whereupon the main switch is rotated by the action of the coil spring through an arc somewhat greater than 90°, or until the bridging or movable contact members have the position shown in Fig. 5, relative to the stationary contacts, and when the switch has been shifted the proper distance the lower jaw 78 of the escapement lever will engage in the notch 76 on the lower side of the escapement disk, causing the switch drum and the movable contact members carried thereby to be brought to a sudden stop. As soon as switch 84 is thrown, the motor 64 begins to rotate, turning the worm wheel and again storing up in the spring energy equal to that expended during the movement of the switch A when the latter was being opened. After a movement of the motor and of the worm wheel sufficient in extent to cause the tension in the coil spring 71 to be the same as the tension prior to the opening of the switch A, the contacts 88 ride off of the contact strip 87 of the drum 85 of the switch 83, breaking the circuit through the motor and coil 81 of the escapement controlling solenoid. The motor immediately comes to a stop but the escapement lever, the ends of which are substantially balanced, remains stationary, holding the escapement disk, switch drum and other parts in position with the switch open. When it is desired to close the switch, all that is necessary is to restore the switch 84 to its original position with the switch blade in engagement with the stationary contact 106, when the circuit will be immediately completed through coil 80 of the escapement controlling solenoid and through the series motor 64, the circuit being completed for the reason that the contact fingers 89 of switch 83 will be bridged by the contact strip 87 of the drum of this switch. The escapement lever will then again be shifted so the jaw 78 will be moved out of the slot 76, and the escapement disk 72 and the switch drum and switch contacts will be rotated by the action of the coil spring until the main switch A is closed, when the upper jaw 77 of the escapement lever will drop into notch 73 of the escapement disk, bringing the rotating parts to a sudden stop. The series motor will then again wind up the spring until the tension of the latter is equal to the tension before this last movement, or until the contacts 89 ride off of the strip 87 of the drum or assume the position shown in Fig. 6. In order that it may be readily seen and positively determined from the front of the 125

switch board whether the main switch is closed or open, I have provided two lamps 115 and 116, one of which is adapted to be illuminated when the switch is closed and the other adapted to be illuminated when the switch is open. In order that this may be automatically accomplished, I have provided a switch 117 including a drum 118 which is secured to the upper end of the shaft 62 and is provided with four contacts 119, 120, 121 and 122, which contacts have the same angular spacing as the notches in the escapement disk. This switch 117 also includes three contact fingers 123, 124, and 125, the former being connected by conductor 126 to one terminal of lamp 116, the second being connected by conductor 127 to conductor 104 and thence to conductor 93 of the operating circuit, and the last named contact finger 125 being connected by conductor 128 to one terminal of lamp 115. The other two terminals of lamps 115 and 116 are connected by conductor 129 to conductor 102 and thence to conductor 94 of the operating circuit. The contact strips and contact fingers of this switch 117 are so arranged that when the main switch is closed the contact fingers 124 and 125 will be bridged either by contact strip 119 or by strip 121 so that the circuit will be completed through lamp 115 only, but when the main switch is open the contacting fingers 123 and 124 will be bridged either by strip 120 or strip 122 so that the circuit through lamp 116 will be completed and this lamp will glow.

The switch which I have described above can be used effectively in circuits of high voltage and large amperage, particularly as the movable switch members are given very quick movements when the switch is opened or closed, and for the further reason that when the switch is opened the movable switch members are swung through greater arcs than is customary in the rotary switches of the double-break type; thus the arcs are very quickly stretched and extinguished before they can do material damage to the contacts.

I do not desire to be confined to the exact details shown, but aim in my claims to cover all modifications which do not involve a departure from the spirit and scope of my invention.

What I claim as new is:

1. In combination, a switch comprising stationary and movable contacts, a spring tending to operate the movable contact of the switch to open and closed positions when it is in closed and open positions respectively, releasable means for holding the movable contact against such tendency in each position, and means independent of the pull of the spring and operative upon each movement of the movable contact for

immediately restoring in the spring an amount of energy substantially equivalent to that expended in producing such movement.

2. In combination, a switch comprising stationary and movable contacts, a spring tending to move the movable contact of the switch to closed or open position according as it is in open or closed position respectively, releasable means for holding the movable contact against such tendency in each of said positions, a motor for winding said spring, and means independent of the pull of the spring and operative upon each movement of the movable contact for causing the motor to wind the spring substantially as far as it unwound in producing such movement.

3. In combination, a switch comprising stationary and movable contacts, a rotary shaft for operating the movable contact both to open and close the switch by movements of the shaft in the same direction, a spring tending to move said shaft in that direction, releasable means for stopping the movement of the shaft when the switch is in open and closed positions, the point of stopping for open position being such that the opening movement is greater than the closing movement, and means for rewinding the spring.

4. In combination, a switch comprising stationary and movable contacts, a shaft for moving the movable contact both to open and closed positions by movements of said movable contact in the same direction, a spring tending to move the shaft in that direction, a motor for winding the spring, means for stopping the movement of the shaft when the switch is in either open or closed position, and controlling means for both causing the release of said stopping means to permit the shaft to move the switch to the other position and the energization of the motor to produce a rewinding of the spring substantially as far as it unwound in producing such movement of the switch.

5. In combination, a switch having co-operating stationary and movable contacts, a rotary drum or shaft carrying the movable contact, an operating motor, a coil spring having one end connected to the shaft and forming the driving connection, between the latter and the motor, means for controlling said spring so that the latter will shift the drum or shaft intermittently to open and close the switch, said means comprising an escapement disk mounted on the shaft and provided with a plurality of notches and an escapement lever adapted to engage said notches, and electrically operated means for shifting said lever.

6. In combination, a rotary, double break switch comprising a pair of stationary con-

- tacts, a rotary shaft having a bridging contact member adapted to engage the stationary contacts, an operating motor mounted above the switch, a coil spring having one 5 end connected to the shaft and having its opposite end connected to the motor, whereby the energy of the motor may be stored in said spring, means for controlling said spring so that the latter will rotate said 10 shaft intermittently in the same direction to open or close the switch, said means comprising a rotary disk having notches on the opposite sides thereof, a pivoted escapement lever adapted to engage said 15 notches, and means for controlling the movements of said escapement lever and of the operating motor.
7. In combination, a frame or casting, switch mechanism supported on the lower 20 side thereof, said mechanism comprising a pair of stationary contacts, a rotary shaft which extends upwardly above the frame or casting and is provided with a movable bridging contact adapted to engage the stationary contacts, a motor mounted on the top of said frame or casting, a coil spring surrounding the shaft of the switch and forming a driving connection between the motor and said shaft, said motor being 25 adapted to store its energy in said spring, and means for controlling said spring so that the latter may intermittently rotate the shaft in the same direction so as to open and close the switch, said means comprising 30 an escapement disk mounted on the shaft and having notches in opposite sides, an escapement lever having jaws adapted to engage said notches, means comprising a pair of magnet coils for shifting said lever, 35 circuits for said coils and for the motor, and switches for controlling said circuits.
8. In combination, a rotary switch having coöperating stationary and movable contacts, a rotary shaft carrying the movable contact, an operating motor, a spring 40 forming a driving connection between the motor and the shaft and adapted to have energy stored therein by the motor, means for permitting the spring to rotate the shaft 45 a predetermined amount to open or close the switch, said means comprising an escapement device including a pair of coöperating members, one secured to the shaft, means for operating said escapement comprising a pair of magnet coils, and means 50 for completing the circuit through one of said coils and through the motor comprising suitable supply conductors and a pair of switches, one of said switches when 55 operated serving to complete the circuit through one of said coils and through the motor and the other serving to interrupt said circuit after a predetermined movement of the motor.
- 60 65 9. In combination, a switch comprising

stationary and movable contacts, a rotary shaft carrying the movable contact, an operating motor, a spring intermediate the motor and the shaft, said spring being wound by said motor and tending to turn 70 the shaft in one direction, means for controlling said spring so that the latter will rotate the shaft a predetermined amount to either open or close the switch, and means independent of the pull of the spring for 75 causing the motor to rewind the spring after each movement of the switch.

10. In combination, a switch comprising stationary and movable contacts, a rotary shaft carrying the movable contact, an operating motor, a spring adapted to be wound by said motor and forming a driving connection between the latter and the shaft, means for controlling said spring so as to permit the latter to turn the shaft a 80 predetermined amount to either open or close the switch, and means independent of the pull of the spring for completing the circuit through the motor so that the latter will wind up the spring after each movement of the switch.

11. In combination, a switch comprising stationary and movable contacts, a shaft for operating the movable contact both to open and closed positions by movements in 95 the same direction, a spring tending to move said shaft in that direction, an escapement for stopping the shaft when the switch is in either closed or open position, electro-magnetically operated means for controlling the escapement, power-operated means for rewinding the spring, and means for simultaneously energizing said electro-magnetically operated means to release the escapement to permit a movement of the 100 switch to its other position and for energizing said power-operated means to rewind the spring substantially as far as it un-wound in producing such movement of the 105 switch.

12. In combination, a main switch comprising stationary and movable contacts, a rotary shaft carrying the movable contact, an operating motor, a spring adapted to be wound by said motor and forming a driving 115 connection between the latter and the shaft, an escapement for holding the spring under tension and for permitting the spring to turn the shaft a predetermined amount to open or close the switch, said escapement comprising a rotary member carried by the shaft and an escapement lever, a pair of coils for shifting said escapement lever, and means for controlling the supply of current to said coils and to the 120 motor, said means comprising suitable supply conductors and a pair of operating switches, one of said switches being located 125 at a distance from the main switch and serving when shifted to complete the circuit 130

- through one of said coils and the motor, and the other switch having a drum mounted on the shaft of the main switch and serving to break the circuit through said coil and said 5 motor after the motor has moved a predetermined amount and has stored in said spring energy substantially equal to that expended when the spring opened or closed the switch.
- 10 13. In combination, a main switch comprising stationary and movable contacts, a rotary shaft carrying the movable contact, an operating motor, a spring adapted to be wound by said motor and serving to turn 15 said shaft in the same direction to close or open the switch, an escapement device for controlling said spring, a pair of coils for operating said escapement device, and means for causing said escapement device to permit the spring to rotate said shaft a predetermined amount and for causing said motor to rewind said spring, said means comprising suitable supply conductors and a pair 20 of switches, one located at a distance from 25 said main switch and serving when operated to complete the circuit through one of said coils and through said motor, and the other being operated by the movement of the motor and serving to interrupt said circuit 30 after said motor has moved a predetermined amount.
14. In combination, a switch comprising stationary and movable contacts, a rotary shaft or drum carrying the movable contact, an operating motor, a spring adapted to be wound by said motor and forming a driving connection between the latter and the shaft, an escapement device for permitting 35 said spring to turn the shaft intermittently 40 in the same direction to open and close the switch, a pair of magnet coils for controlling said escapement device, and means for causing said escapement device to permit the spring to turn said shaft a predetermined 45 distance and causing said motor to rewind said spring, said means comprising suitable supply conductors and a pair of switches, one of said switches being located at a distance from the main switch and serving 50 when operated to complete the circuit through one of said coils controlling the escapement and said motor, and the other having a drum which is operated by the movement of the motor and serves to break said 55 circuit after the shaft has been shifted a predetermined amount by said spring and after the motor has restored in said spring substantially as much energy as was expended in producing such movement.
- 60 15. In combination, a switch comprising stationary and movable contacts, a rotary shaft or drum carrying the movable contact, an operating motor, a spring adapted to be wound by said motor and forming a 65 driving connection between the latter and the shaft, and means for controlling said spring so as to permit the latter to rotate the shaft intermittently in the same direction to open and close the switch, said controlling means comprising an electrically 70 operated escapement including an escapement disk mounted on the shaft and the escapement lever, said disk having notches adapted to be engaged by said lever, the annular spacing of such notches being such 75 that the movement of the shaft when the switch is being opened is greater than when the switch is being closed.
16. In combination, a double break rotary switch, comprising a pair of stationary contacts and a movable bridging contact, a shaft carrying said bridging contact and adapted to be rotated intermittently in the same direction to open and close the switch, an operating motor for said switch, a spring adapted to be wound by said motor and to operate said shaft, and an escapement for said 80 spring comprising a notched disk and an escapement lever adapted to engage said notches, the annular spacing between certain of such notches being greater than between certain other notches in order that the movement of the shaft when the switch is being opened will be greater than the movement of the shaft when the switch is being 85 closed.
17. In combination, a switch comprising stationary and movable contacts, a shaft carrying the movable contact and rotatable in the same direction both to open and close 90 the switch, a spring tending to move the shaft in that direction, an escapement for stopping the shaft at open and closed positions of the switch, the open position being such that the opening movement is greater than the closing movement, two electromagnets for releasing said escapement to allow the movement of the shaft to open and close the switch respectively, a motor for rewinding the spring, and means for energizing 95 said motor and that one only of the electromagnets which will release the escapement, and for deenergizing said motor and magnet when the motor has rewound the spring substantially as far as it unwound in producing a movement of the shaft and switch resultant upon such release of the escapement.
18. In combination, a switch comprising stationary and movable contacts, a shaft carrying the movable contact and rotatable in the same direction both to open and close the switch, a spring tending to move the shaft in that direction, an escapement for stopping the shaft at open and closed positions of the switch, two electromagnets for releasing said escapement to allow movement of the switch to open and close the switch respectively, a motor for rewinding the spring, said motor being connected in 110

- 130

series with both of said magnets and the two magnets being in branch circuits in shunt to each other, and means for completing the circuit of the motor and of that magnet only which will release the escapement.

19. In combination, a switch comprising fixed and movable members, a spring tending to move the movable member both to open and closed positions by movements in the same direction, an escapement for controlling the movement of the movable member of the switch, electrically-operated means controlling the escapement, a motor for winding the spring, and means for controlling said electrically-operated means to release the escapement to permit a movement of the switch to the other position than that it happens to occupy and for causing the energization of the motor to cause the immediate rewinding of the spring.

20. In combination, a switch comprising fixed and movable members, a spring tending to move the movable member of the switch in the same direction to open and closed positions, an escapement for stopping the switch in either closed or open position, two magnets for releasing said escapement when the switch is in open and closed positions respectively, a motor for winding the

spring, said magnets being in branch circuits in shunt to each other and in series with the motor, and means for completing the circuit of the motor through that magnet only which when energized will release the switch.

21. In combination, a switch comprising fixed and movable members, a spring tending to move the movable member of the switch in the same direction to open and closed positions, an escapement for stopping the switch in either closed or open position, two magnets for releasing said escapement when the switch is in open and closed positions respectively, a motor for winding the spring, said magnets being in branch circuits in shunt to each other and in series with the motor, and means for completing the circuit of the motor through that magnet only which when energized will release the switch, and for breaking such circuit when the motor has rewound the spring.

Milwaukee, Wis., March 30, 1909.

In testimony whereof I affix my signature, in the presence of two witnesses.

HERBERT W. CHENEY.
